(57) **CLAIM**

The ornamental design for an instrument cover for lift truck, as shown.

DESCRIPTION

This application is related to U.S. patent application entitled Instrument Cover for Lift Truck (Ser. No. 29/409,209), which is filed concurrently herewith.

FIG. 1 is a perspective view of an instrument cover for a lift truck as seen from the top, rear and right side showing our new design and the environment of a fork lift truck which uses the instrument cover;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line showings in the figures are for illustrative purposes only and form no part of the claimed design.
